Fisher Steadman
Gettys Patent

The Schedule referred to in these Gettys Patent and making part of the same containing a description in the words of the said Fisher Steadman himself of his improvement in the method and machinery for matching & dressing boards and plank for floors roofs & other purposes

To all persons to whom these presents shall come: Be it known that I Fisher Steadman of Aquachanack in the County of Essex and State of New Jersey have invented a new and useful improvement in the method and machinery for matching and dressing boards & plank for floors roofs and other purposes. And that the following is a full and exact description of the construction and operation of the said machine as invented by me. This machine consists of a substantial frame 8 feet long 2 $\frac{1}{2}$ feet wide and 2 $\frac{1}{2}$ feet high formed by connecting 4 corner posts at the top by plates and beams all round and by connecting the posts at the bottom by two girders on each side of the frame and by fanning the lower ends of the posts into two cross pieces which projecting 6 feet beyond the posts forms a side support to keep it steady on the floor. This frame work is represented on the drawings and by the model accompanying this specification and is marked A. And in the following description of this machine that end having on it the driving shaft and from which the boards when dressed are delivered will be called the front end and the opposite the back end. And the side having on it the driving pulley will be called the pulley side and the opposite the gear side. On the outside of the front post one foot upwards from the cross piece or foot are bolted the bearings or caps to sustain the main shaft marked a. From the inside of each plate 6 feet from the front end a slotted stand is projected upwards the post forward of the slit rising perpendicularly about 6 inches the other is turned back at the top to receive the pin of the dressing lever. The bottom of the slit serves as a bearing for the moving roller which carries forward the board to be dressed and dovetailed and the upper part of the slit serves as a guide to the dressing roller these stands are marked b, about 5 $\frac{1}{2}$ feet from the

the front of the frame or post is secured to the girths and plates of the frame on the inside and perpendicular to them rising 8 $\frac{1}{2}$ feet above the top of the plates. And 1 $\frac{1}{2}$ feet from the post are similar ones in all respects the upper end of each is connected with its fellow on the same side of the frame by two girths one at the top and the other 5 $\frac{1}{2}$ feet down leaving a space of 8 $\frac{1}{2}$ feet between them and arranged with keys to adjust them. on these girths are the bearings of the shafts of the two dove tail cutters marked c.c. and the shaft of the pressing roller marked d.d. and the shaft of the straightening saw marked e.e. 6 $\frac{1}{2}$ feet from the front end a bridge tree rests on and is secured to the plates to form and hold the upper bearing of the upright cutter shaft marked B. and directly under and perpendicular to this is a similar piece resting on and secured to the girths below to sustain the step of the upright shaft. this piece is marked C. seven feet from the front end are projected stands similar in all respects to those marked b.b. to sustain a like roller and pressing roller near the back end of the machine to carry out the board when finished. these stands are marked f.f. A piece of plank is then secured to the top of the end beams raising them to a level with the upper surface of the bridge tree. On the top of the plates as many beams as are necessary (say three) to support the frame and work are placed extending across the frame with their upper surfaces level with the last mentioned pieces. On the back beam and on the bridge tree is a stand fitted to hold a roller to prep the board edgewise to the guide hereafter mentioned. these stands are moveable to admit different sized boards and project towards the front of the machine and are marked g.g. 9 $\frac{1}{2}$ feet of a foot from the rear side and parallel with the plate, and on the upper surface of the beams and bridge tree a guide is extended the whole length of the frame to govern the lateral motion of the board and is marked D. When all these parts and pieces are thus adjusted, the main shaft marked C. is entered in its bearings having on the pulley end outside the frame a fast and loose pulley 12 inches in diameter and at 2 inches from the post inside the frame a pulley 15 inches in diameter marked b.b. to drive the circular straightening saw and another from this pulley another pulley marked c. 15 inches in diameter to drive the upper dove tail cutter. And 2 inches from this

This pulley, a pulley marked $\frac{1}{2}$ q inches in diameter to drive the upright cutter or traverse wheel shaft. Above 3 inches from this a pulley marked $\frac{1}{2}$ 15 inches in diameter to drive the under dove tail cutter and on the gear end of the shaft outside of the frame is a pulley, 3 inches in diameter marked $\frac{1}{2}$ to drive the gearing, & carrying roller extending across the frame 12 inches in diameter marked m, m, is placed in each of the slotted stands so that the board when entered upon them will just clear the bridge tice and beams having on each near their gear ends a cog wheel of 18 teeth and on the extreme ends a cog wheel of 36 teeth marked n, n. The upper and lower dove tail cutter shafts are then entered in their bearings having on them each a pulley 4 inches in diameter and in a line with their respective driving pulleys on the main shaft. And each a dove tail cutter with their noses so formed as to shape the dove tail as required these cutters are marked o, o, and are situated as to form the dove tail on each edge of the board on opposite sides and each to cut the board half through. The friction roller shaft is then placed in its bearings having on a friction roller 4 inches in diameter bearing on the board to keep it steady to the action of the cutters and saw, this roller is marked p. The shaft of the straightening saw is then entered on its bearings having on it a pulley 4 inches in diameter in a line with its driving pulley on the main shaft. and also a common circular saw which cuts the board to its proper width. This saw is marked q. The upright cutter shaft is then placed in its step and bearings marked R and has upon it a pulley marked r, q inches in diameter and in a line with its pulley on the main shaft marked p, and on the top a horizontal cutter wheel marked G, 13 $\frac{1}{4}$ feet in diameter and 3 inches thick having four or more cutter rests projecting from its periphery 1 $\frac{1}{2}$ inches and standing diagonally (say) 45 degrees to its perpendicular. in these rests is cut a female screw to hold the cutters in place. These cutters are formed with a slot through which the said screw passes and are held by its head firmly to the rests and are circular on the edge that when they pass or traverse the board they cut like a gouge and are marked t. An upright stand marked H, to hold a pulley & gear

gearwheel is then secured to the guide & placed 4 feet from the front end on the gear side outside of the frame. And in this piece 1 $\frac{1}{2}$ feet from the gear a stud is fixed to hold a pulley 9 inches in diameter marked m , having on the inside and connected with it a cogwheel of 18 teeth directly over this and at such a distance as to gear properly into it is a stud holding a gearwheel of 6 teeth marked n , and on each side of the last mentioned wheel is an intermediate or stud wheel on studs secured to the plates of 6 teeth marked n , and gearing also into the wheels on the moving roller marked n, n , the pressing rollers are then placed in the slotted stands having on their gearends a cogwheel of 18 teeth marked x, x to gear into the small wheels on the moving roller shaft and having a bore turned in the bearing outside of the stand to receive the pressing levers. Which levers are marked l , and are secured to the curved part of the slotted stands by a bolt on which they play freely and rest on the sides of the pressing rollers and are then projected to any suitable length and weighted at each end as shown by the model on the pulley side or they may be continued coll to coll as shown on the gear side of the model and weighed between the collars. The horizontal guiding pulleys marked y, y 4 inches in diameter are then placed in their stands q, q , so as to bear against the edge of the board opposite to the rest and compel it to keep up to it. When all these parts and pieces are thus formed and adjusted pass a belt from the first pulley mentioned on the main shaft inside of the frame and around the pulley on the shaft of the circular saw, then a belt round the next pulley mentioned and around the pulley on the shaft of the upper dove tail cutter shaft. Then a belt around the next pulley mentioned on main shaft and around the pulley on the upright shaft then a belt around the next pulley on main shaft and around the pulley on the under dove tail cutter shaft, then pass a belt around the pulley on the gear end of the main shaft and around the pulley marked m , having on it the gear wheel. Then a pass a belt from the moving power of the mill around the last pulley on the main shaft and all will be in motion. Then enter a board between the front moving and pressing rollers taking care to keep it up to the guide

piece with a safety or tail and it will be drawn in by the motion of the rollers until it reaches the dove tail notch when a dove tail will be cut on each edge opposite sides. The saw will cut it to a width of each end and the cutter on the wheel. It will traverse the upper side and drift it to a thickness and by passing over it will leave it perfectly dressed and smooth on the surface and it will be passed out of the machine in form of the minia-
ture piece marked No. 11 in the model and as soon as one board is fully on-
end another may be put in and the machine be kept constantly at work
until the boards will match truly and form with each other perfect

joints when laid together. The advantages of this machine consists when drift-
ing boards for roofs is that each dove tail will form a trough by which
water will always be passed without leak to the end of the board and
for whatever purpose they may be used this mode of matching has this ad-
vantage that the joints become closer instead of opening by a slight shrink-
ing of the board which must give a decided advantage in floors and
for all purposes where the object is to keep out cold and wet, and by
traversing the cutter across the board I am enabled to dress boards of the
hardenst timber as well as of the softer kind. What I claim as new in
this improvement is the whole of the apparatus and combination of
machinery by which the board is traversed by the cutter in dressing the
surface and by which the edges are matched in the dove tail form as
described above and is the invention for which a Patent is now prayed
In witness that the foregoing is a true description and specification of
my said improvement I have hereunto set my hand this 12th day of

June 1835.
